UNITED STATES PATENT OFFICE

152,454

DESIGN FOR A BRACELET OR THE LIKE

Herman Bogoff, Chicago, Ill.

Application December 6, 1947, Serial No. 142,990

Term of patent 7 years

(Cl. D45—4)

To all whom it may concern:

Be it known that I, Herman Bogoff, a citizen of the United States, residing in Chicago, in the county of Cook and State of Illinois, have invented a new, original, and ornamental Design for a Bracelet or the like, of which the following is a specification, reference being had to the accompanying drawing, forming part thereof.

Fig. 1 is the front view of a bracelet or the like, showing my design, and

Fig. 2 is the side view thereof.

I claim:
The ornamental design for a bracelet or the like, substantially as shown.

HERMAN BOGOFF.
